GAS HEATER

Richard E. Fraser, Stockton, Calif., assignor to
 Fraser Furnace Company, Stockton, Calif., a
 corporation

Application February 8, 1935, Serial No. 5,569

8 Claims. (Cl. 126—116)

This invention relates to the heating art and particularly to a gas fired heating unit of that type commonly known as a floor furnace as distinguished from the usual central unit basement furnace.

As heretofore commonly constructed and used the so-called floor furnace comprises an outer casing adapted to be suspended from and below the floor of a room. Spaced substantially equally from all four of the side walls of the casing is a central heating chamber having therein a gas heater. Air moves from the lower to the upper end of the heating chamber past the heater where the heat exchange takes place. The heated air then flows out of a grate set on the top of the heating chamber, the top of which chamber is set at the floor level of the room. Cooler air returns from the room through the grating also at floor level and through the space between the outer casing of the walls of the heating chamber, which return air enters into the heating chamber at the bottom thereof where it is reheated and again discharged into the room. A fair example of such a floor furnace is shown in my Patent No. 1,952,009.

Certain disadvantages are inherent in the use of a furnace of this type. In order to use a unit sufficiently large to properly heat a room it often happens that the width thereof is so great that even if the unit is placed close to a wall it becomes necessary to cut into the edge of the rug in the room in order to fit it around the heater. Also the center grate through which the heat is rising becomes very hot and oftentimes children playing on the floor will be burned by coming in contact therewith.

The primary object of my improved invention therefore is to provide a heating unit which will have all the advantages of the floor unit but which will do away with the above and other inherent disadvantages thereof.

This object I accomplish generally by providing what may be termed a combination floor and wall furnace in which the heating chamber and return air inlet, constituting what may be termed the floor portion, are still suspended below the floor but in which the hot air discharge grill element, constituting what may be termed the wall portion, is positioned against and discharges transversely outwardly from a wall of the room. This novel structure is carried out by means of such novel relative arrangements of parts as will more fully appear from the following specifications and claims.

In the drawings similar characters of reference

indicate corresponding parts in the several views:

Fig. 1 is a perspective view of my novel heating unit.

Fig. 2 is a vertical section taken on a line 2—2 of Fig. 1.

Fig. 3 is a top plan view, partly broken out, of the heating unit with the wall portion removed.

Fig. 4 is a fragmentary view, partly in section, showing the joint between the removable wall portion and the floor portion of the unit.

Fig. 5 is a fragmentary view partly in section showing the joint between the removable heating chamber element and its support.

Fig. 6 is a vertical transverse section through the wall portion of the unit.

Referring now more particularly to the characters of reference on the drawings, the numeral 1 designates the outline of the floor of a room, and the numeral 2 an adjacent wall thereof.

As indicated in the preamble to this specification, the present invention anticipates the combination of floor and wall portions. The floor portion comprises generally the heating chamber and the return air passageways with a heater disposed within the heating chamber. The wall portion of the unit comprises generally the heat outlet grill element connected with the heating chamber which is located below the floor and which grill extends above the floor and immediately adjacent the wall and presents an appearance very similar to that of an ordinary heat discharging grill used on the outlet conduit of a basement furnace.

Fig. 1 of the drawings shows generally the entire unit disassociated from its location in the floor, while Fig. 2 is a vertical section thereof showing it as it appears mounted in the floor with the heat discharging element extending immediately adjacent the wall. The numeral 3 designates the substantially rectangular outside casing of the floor portion, which casing is provided at its upper edges with outwardly turned flanges 4 which extend over and are supported by the flooring 1, a proper opening being cut in the floor and the floor being properly braced in order to support the same.

The heating unit is suitably supported from the bottom of the casing 3 and projects vertically into the casing and comprises generally a main gas heater 5 below which is the gas burner 6 which discharges the heated products of combustion into the heater 5.

The heater 5 terminates short of the top of the casing 3 and is provided with a pair of outlets 7, each communicating with a substantially oval shaped conduit 8. Each conduit 8

55

extends vertically adjacent the heater 5 and terminates at its lower end in an outlet pipe 9 which communicates with an outlet casing 10 common to both conduits 8 and having in turn 5 a single outlet flue 11 projecting outside the front wall of the casing 3. Heat radiating hollow fins 12 project outwardly from the side walls of the heater 5 and have communication therewith.

The heated products of combustion from the 10 burner 6 pass through the heater 5, outlets 7, conduits 8, outlets 9, and finally through the casing 10 and single outlet 11 to the flue. The gas heater 5 is placed closely adjacent the rear wall of the casing 3 so as to enable the unit to 15 be installed in the floor closely adjacent the wall and still allow of the proper recirculation and heating of the air in the room in the manner as will presently appear. The air heating chamber surrounds this gas heater 5 and comprises generally a rectangular casing A which 20 comprises spaced walls 13 and 14 respectively to provide a hollow wall entirely around such casing for a purpose as will presently appear. This casing A extends over the gas heater 5 and its 25 associated parts and rests at its bottom on two crossbars 15 extending from front to rear of the casing 3. These bars have inturned flanges 16 which extend inside of the walls 13-14 of the casing A and function to guide the casing into 30 place when it is set in position within the casing 3, and these flanges 16 also prevent lateral displacement of the casing A after it has once been placed in position. It will be noted that this 35 casing A is not definitely connected to the bars 15 but may be readily removed therefrom. The casing A is cut away as at 17 to fit over the outlets 9.

When the casing A is in position within the casing 3 the back wall thereof is spaced only a 40 slight distance from the back wall of the casing 3 to form a narrow air passage-way 18. A panel 19 is mounted on the inside of the back wall 13 of the casing A and spaced a short distance therefrom to provide an air passageway 20 between the back wall 13 and the gas heater 5. The back wall of the casing 3 has a plurality of 45 orifices 21 and 21a adjacent the top edge and bottom thereof respectively, while the back wall 14 has a plurality of orifices 22 adjacent the lower edge thereof and the inner wall 13 of the casing A has a plurality of orifices 23 adjacent the upper edge thereof and completely around the entire inner circumference of the wall 13.

The front and side surfaces of the casing A 55 are spaced a considerable distance from the front and side inner surfaces of the casing 3 to provide a considerable air space 24 between such sides of the casing 3 and the casing A. The front hollow wall 13-14 of the casing A adjacent the top edge thereof is inclined backwardly as at B to form a restricted outlet C at the top of the casing A. Surrounding this outlet C and supported on the top edges of the casing 3 is a return air inlet grate 25. Air returning from the room to 60 the heating unit passes down this grate and through the space 24 and hence into the heating chamber formed around the heater 5 by the casing A and thence to the outlet C thereof. Such air during this travel is thoroughly heated by 65 contact with the heat radiating from the gas heater 5 and its associated parts. This heated air is then discharged back into the room through the wall portion D of the unit which is in communication with the outlet C.

70 The wall portion comprises generally a casing

D having inturned flanges 26 at its lower edge adapted to removably fit over cooperating flanges 27 projecting upwardly from the side of the casing A around the outlet C. Those cooperating flanges on the back of the unit are removably attached together by wing nuts 28 threaded through the same. These wing nuts can be reached from the front of the unit when the cover grill 31 is removed.

The backs and sides of the grill casing D are 10 provided with thick insulation mats 29 to insulate the same against the possibility of the adjacent wall being scorched or set on fire by the heat which pours out through this wall portion of the unit. Further insulation is provided at this point 15 by reason of the fact that this insulating mat 29 is spaced from the side walls of the casing D and from the wall 2 when the casing D is fitted against the wall whereby the casing between its side walls and this mat and between the mat and the wall is provided with an air space 18a in communication with the air space 18. (See Fig. 6.) A plurality of inlet orifices 30 are provided in the side and top walls of the casing D whereby air 20 will be drawn from the room through these orifices and down through the space 18a and space 18, thence through the orifices 22 into the hollow wall 13-14 of the casing A, and thence through the orifices 23 back into the heating chamber A. This circulation of air further tends to insulate 25 the wall portion from the adjacent wall and also to insulate the back wall of the casing 3.

This latter action is enhanced by reason of the fact that additional cool air from underneath the floor is drawn through the orifices 21 down 30 through the space 18 and through the orifices 22 into the hollow wall 13-14 of the casing A. It will be noted that these insulating features 35 are of great importance and form a primary part of the present invention, since it is absolutely essential that in view of the fact the heating unit is placed so close to the wall every chance of overheating or setting fire to the wall must be avoided and this is fully taken care of by these 40 several features of insulation.

Over the face of the casing D is fitted the outlet grill 31. This grill has small inturned tongues 32 at its lower edge which fit through corresponding slits in the bottom face of the casing D. The grill at its upper end is fastened in position by 45 small thumb catches 33. By turning the catches so as to release the upper edge of the grill the grill may then be removed from the front of the casing by withdrawing the tongues 32 from their cooperating slots. The wing nuts 28 may then be 50 reached to disconnect the grill element from the top of the casing A and it may be also removed. The grate 25 may then be lifted clear of the casing 3 and thereupon the casing A may be removed 55 from its supporting bars 15. This method of assembly and disassembly of the parts is an important feature of the invention in that it permits the several elements to be taken out when it is desired to clean out the heating unit. This 60 is necessary to be done quite often since the grills being open to the room, dust and debris from the room is very apt to fall through the same.

The arrangement of parts whereby I am enabled to bring the outlet 18-11 to the front of the unit is quite novel and useful. By this arrangement the flue pipe may be carried in any direction away from the unit. This is a great advantage when encountering beams or other obstructions which cannot easily be avoided when 65

the vent is arranged at one end of the unit as is now the general commonly used construction.

It will be apparent from the foregoing description of the construction and relative arrangement of the parts that my improved heating unit has a floor portion and a wall portion, the backs of which lie substantially in line with each other and are adapted to lie parallel with and adjacent to a wall of a room. The floor portion of the unit is so constructed as to well sustain the heating chamber and the heater therein, with ample room around the sides and front thereof to provide for the recirculation of air from the room into the heating chamber. The wall portion of the unit then projects into the room proper immediately adjacent the wall, giving the appearance of an ordinary basement furnace outlet grill, but being in fact admirably adapted to receive and discharge the heated air from the floor portion. Thus is provided a very compact and neat appearing unit avoiding the disadvantages of an ordinary floor furnace, while maintaining all of its advantages. It will also be obvious that the structure of the back walls of both the floor and wall portions of the unit is admirably adapted to provide complete and efficient insulation properties without any great expense or addition of heavy and unwieldy parts.

An air circulating fan may be desired to be installed in the wall portion D to step up the circulation and increase the efficiency of the unit.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

45 1. A gas heating unit including a floor portion which comprises an outer casing, a heater disposed within the casing closely adjacent the back wall thereof, a second casing which is open at both ends and surrounds the heater to form a heating chamber, the back wall of the second casing lying close to the back wall of the first casing and spaced a relatively much greater distance from the front and side walls thereof, an air inlet grate over the top of the second casing, an outlet grill casing communicating in substantially vertical alinement with the upper open end of the heating chamber, and a discharge grill forming one upstanding face of the last named casing to discharge air therefrom, the grill casing having hollow walls on the other three sides forming air spaces which are in communication with the space between the first and second named casings, the outer portion of the hollow walls being provided with a plurality of orifices.

60 2. A heating unit comprising an outer casing, supporting elements arranged within said casing adjacent the lower end thereof, a second open ended casing disposed within the first casing and mounted on said supports, the second casing being disposed closely adjacent the back wall of the first casing and spaced a relatively much greater distance from the front and side walls thereof, a heater disposed within the second casing, an open grate mounted on the top of the first casing around the upper open end of the second casing,

and a third casing mounted on the upper edge of the second casing and in communication in substantially vertical alinement therewith, the third casing having an open outlet grill in one upstanding face thereof and having hollow walls in open communication with the space between the first and second casings, the hollow walls having perforations in their outer portion and the back wall of the second casing having perforations adjacent the upper edge thereof.

65 3. A combination floor and wall furnace comprising an open topped rectangular casing adapted to depend from an opening in a floor of a room and with its back adapted to project adjacent and outwardly of the vertical plane of a wall of the room, an inner casing in said depending casing spaced therefrom and forming a heating chamber while the space between said casings forms an air inlet chamber communicating with the room in front and at the sides of the heating chamber, a third casing upstanding from and covering the top of the heating chamber and the adjacent top portions of the inlet chamber at the sides, the sides and top of the third casing extending to the back thereof, said third casing having heat insulating back and inner side walls spaced from the sides of the third casing so that the spaces between said sides and inner side walls are in communication with the inlet chamber while the third casing inwardly of said heat insulating walls is in communication with the heating chamber, and an air outlet grill in the front of the third casing; there being openings in the sides of said third casing for the admission of air from the room.

70 4. In a floor and wall furnace unit, a discharge casing for hot air adapted to upstand from the floor separate from and outwardly of a wall, the sides and top of the casing adapted to extend to said wall and the front of said casing having outlet openings, inner heat insulating side and back walls in the casing spaced from the sides of the casing and adapted to be spaced from the wall, means below the casing to heat air and deliver the same to the casing for discharge into the room, and means functioning with the operation of the heating means to circulate relatively cool air through the enclosed spaces in the casing outwardly of said insulating walls.

75 5. In a floor and wall furnace unit, a discharge casing for hot air adapted to upstand from the floor separate from and outwardly of a wall and adapted to be disposed with its back adjacent said wall, heating means in the unit to heat and deliver hot air to said casing for discharge into the room, and means functioning with the operation of the heating means to keep the casing at the back relatively cool to prevent possible overheating of the wall.

80 6. A floor and wall furnace unit comprising a grate adapted to be supported on a floor over an opening therein, a casing forming a heating chamber depending from the grate and also projecting upwardly therefrom a short distance, and another casing having air outlet openings in its front face removably resting on and upstanding from the grate and removably surrounding and engaging the upwardly projecting portion of the first named casing.

85 7. A floor and wall furnace unit comprising a grate adapted to be supported on a floor over an opening therein, a casing forming a heating chamber depending from the grate and also projecting upwardly therefrom a short distance, another casing having an open front removably resting on and upstanding from the grate and

removably surrounding and engaging the upwardly projecting portion of the first named casing, a removable air outlet grate mounted over the front of said other casing, and a removable bolt connecting the upwardly projecting portion of the first named casing with the adjacent portion of the second casing and accessible upon removal of the grate thereof.

8. A floor and wall furnace comprising a casing adapted to depend from the floor, a heating chamber in said casing, another casing having air out-

let openings in the front upstanding from the first named casing, a vertical back wall on said upstanding casing, and orificed top and side wall extensions on said upstanding casing projecting rearwardly of the back wall thereof for engagement with a wall of the room in which the furnace is mounted, whereby to maintain said back wall spaced from the room wall when the furnace is installed.

RICHARD E. FRASER. 10
